[57] CLAIM

The ornamental design for a table top air filter unit for
removing hazardous fumes, as shown and described.

DESCRIPTION

FIG. 1 is a front elevation view of a table top air filter
unit for removing hazardous fumes, showing my new
design;

FIG. 2 is a rear elevation view thereof;

FIG. 3 is a top plan view thereof;

FIG. 4 is a bottom plan view thereof;

FIG. 5 is a right side elevation view thereof, the left side
being a mirror image of that shown; and

FIG. 6 is an exploded perspective view thereof, show-
ing the hood portion separated from the filtering portion.

FIG. 1

FIG. 2

FIG. 3

FIG. 4

FIG. 5

FIG. 6
